Primary Examiner—Alan P. Douglas*Assistant Examiner*—Lavone Tabor*Attorney, Agent, or Firm*—Foley & Lardner[57] **CLAIM**

The ornamental design for a brush keeper, as shown and described.

DESCRIPTION

FIG. 1 is a top plan view of a brush keeper in an open position;

FIG. 2 is a left side view in an open position of a brush keeper, the right side view being a mirror image thereof;

FIG. 3 is a left side view of the brush keeper in a closed position, the right side view being a mirror image thereof.

The bottom and front and rear ends of the article, neither shown in the drawing nor described in the specification, form no part of the claim design.
